CLAIM

The ornamental design for the dental cabinet, as shown and described.

DESCRIPTION

FIG. 1 is an isometric view of our new dental cabinet design, depicting the environment;

FIG. 2 is an enlarged isometric view of FIG. 7;

FIG. 3 is an enlarged isometric view of an upholstered column and shelf thereof;

FIG. 4 is a front elevation view thereof;

FIG. 5 is a left-side elevation view thereof (the right-side elevation view being a mirror image of FIG. 5); and,

FIG. 6 is a top plan view thereof.

The broken dot-dash lines throughout the figures of the dental cabinet are intended to denote environment structure. Neither the broken dot-dash lines themselves, nor the regions within the lines, form any part of the claimed design. The stippled portions of the dental cabinet design shown throughout the figures are intended to denote a fabric-like or upholstered appearance.
